ARMORED SAND DISPENSING VEHICLE

Marcus J. Dill, Dallas, Tex., assignor to The Western Company of North America, Fort Worth, Tex., a corporation of Delaware

Filed May 16, 1969, Ser. No. 17,184

Term of patent 14 years

Int. Cl. D12—09

U.S. Cl. D14—3

FIG. 1

FIG. 2

FIG. 3

FIG. 4

FIG. 5

FIG. 6

FIG. 1 is a perspective view of an armored sand dispensing vehicle showing my new design;

FIG. 2 is a front elevation view thereof;

FIG. 3 is a back elevation view thereof;

FIG. 4 is a top plan view thereof;

FIG. 5 is a side elevation view thereof; and

FIG. 6 is a bottom view thereof.

I claim:

The ornamental design for an armored sand dispensing vehicle, as shown.
